UNITED STATES PATENT OFFICE.

FRANKLIN A. UMSTED, OF CHICAGO, ILLINOIS.

CARPET-SWEEPER.

1,181,268.

Specification of Letters Patent.

Patented May 2, 1916.

Application filed July 9, 1915. Serial No. 38,855.

To all whom it may concern:

Be it known that I, FRANKLIN A. UMSTED, a citizen of the United States, residing at Chicago, in the county of Cook and State of Illinois, have invented certain new and useful Improvements in Carpet-Sweepers, of which the following is a specification.

This invention relates to improvements in carpet sweepers and one of the objects of the invention is to simplify the construction of the same and produce a carpet sweeper which will be simple, durable, light, cheap and of a rigid construction.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating the invention, and in which:

Figure 1 is a central vertical transverse sectional view of an improved sweeper of this character constructed in accordance with the principles of this invention. Fig. 2 is a top plan view of one end of the sweeper. Fig. 3 is an enlarged detail horizontal sectional view of one corner of the sweeper showing the manner of securing and holding the bumper in position. Fig. 4 is an enlarged detail elevation of one corner of the sweeper frame showing the bumper receiving notch.

Referring more particularly to the drawing, the numeral 10 designates a single piece of sheet material such as metal bent into shape to form the top and sides of the casing. The ends 11 of the casing are formed of sheet material each provided with a flange 12 at the top thereof and projecting laterally therefrom so as to extend under the end of the top 10, and these parts are secured together in any desired or suitable manner such as by means of spot welding 13. The casing thus formed may be of any desired size and configuration and the corners are secured together in any suitable manner preferably by extending a portion

of the cover 10 adjacent the front and rear wheels of the sweeper so as to project a short distance beyond the ends 11 to form a projecting ear 14, and this ear is provided with an open recess 15. The ends of the end 55 pieces 11 adjacent the projecting portions 14 of the cover 10 are deflected laterally as at 16, see particularly Fig. 3, so as to rest against the ears 14, and the extremities of the projections 16 are also notched as at 17 60 to correspond with the recesses 15. These portions of the cover and ends are secured together preferably by means of fastening devices 18 in the form of bolts passing through registering apertures therein and 65 nuts 19 secured to the bolts.

The end portions 11 are provided with recesses 20 which open through the lower edge thereof to receive the core 21 of the brush 22.

Extending across the ends of the casing, and parallel with the end portions 11 thereof are wheel guards 23, constructed of any suitable sheet material and are held spaced from the end portions 11 by means of the 75 ears 14 and the deflected portions 16 of the end portions 11, and these guards 13 are secured in position by means of the fastening bolts 18 which extend through the extremities 24 of the guards and which latter are deflected to rest against the front and rear face of the casing.

The brush 22 is rotatably supported preferably by the wheel guards 23 which latter are provided with suitable bearings, in 85 which the projections 25 on the core 21 of the brush are journaled and the brush is provided with a friction disk 26 at each end thereof, which disks are positioned between the respective pairs of wheels 27, as 90 is usual in sweepers of this character.

The wheels 27 are each mounted upon an axle 28, constructed of spring material and these axles extend through enlarged openings 29 in the end portions 11 so as to give 95 the necessary spring movement to the wheels and to allow the casing together with the brush to be pressed downwardly toward the floor during the operation of sweeping.

The wheels 27 are mounted on the outside 100

of the casing and washers 30 are provided on the axles to form closures for the openings 29.

In order to give the necessary springing 5 action to the wheels, and to secure the axle in position, there is provided for each of the axles, a bar or rod 31, which is provided with a bifurcated extremity 32 in which bifurcation the axle 28 is seated and 10 the extremities 33 of the arm are deflected around the axle so as to hold the parts against dislocation. The other extremity of the bar or rod 31 is loosely positioned within a seat 34 formed in the casing 15 10 which seat is formed by offsetting a portion of the casing. These portions are offset from the inside of the casing so as to form projections extending from the outer face of the casing and one on each side of the machine, and these projections form the stops or bumpers against which the socket 35 of the handle bail 36 strikes, when the bail is in a folded position, the offset portion 34 serving the double function of a seat for the 20 25 anchor bar 31 and a bumper for the handle bail. These axles 28 rest upon the bottoms of the openings 29 and the centrally arranged bars or rods 31 tend to hold the axles in position while the axles in turn, being of 30 an elastic or yielding nature, hold the ends of the bars or rods 31 seated in the recesses formed by the offset portions 34.

A bumper 37 in the form of a band is provided and surrounds the casing on the outside thereof, at a considerable distance from the base of the casing and this bumper 37 may be held in position against displacement in any suitable or desired manner, preferably by notching the corners of the 40 wheel guards 23 to form a recess, into which a portion of the band is seated. These recesses are formed preferably by cutting the material on each side of the corner to form a portion 38, which is partially severed from 45 the wheel guards, and the portion which is thus partially severed is located in alignment with the recess 15 and the corresponding notch in the end piece 16. The partially severed portion is then deflected inwardly as shown more clearly in Fig. 3 to 50 form a recess 39.

The brush 22 is located preferably at the middle of the casing and extends entirely thereacross, and on each side of the brush 55 is arranged a dust pan 40, which is also preferably constructed of sheet material and is of any desired size and configuration. Each of the pans 40 is pivotally supported adjacent one edge as at 41, and an operating 60 handle or lever 42 is provided for swinging the pan about its pivot. This handle 42 is preferably pivotally connected as at 43 with a portion of the pan and extends through a

slot 44 in the top of the casing and the projecting extremity of the handle 42 is deflect- 65 ed as at 45 to provide a convenient means for operating the latter.

A spring 46^a is connected with the pan and the handle and tends normally to hold the pan in a closed position. The bumpers 70 against which the pans 40 abut when in a closed position are preferably formed by bending the edges of the front and rear of the casing at the bottom thereof back upon itself as at 46, for any suitable distance to 75 form a reinforce for the edge of the casing and then deflecting the free extremity of this bent portion laterally as at 47 to form a ledge against which the edge of the pan strikes. 80

If desired in order to hold the handle bail in an upright position when the sweeper is not in use, portions of the end pieces 11 may be deflected or offset as at 48 to form projecting ribs between which a notch 49 is arranged and into which the handle bail springs when the latter is raised. 85

With this improved construction it will be manifest that the entire sweeper is constructed of metal and that there is no wood present in this structure, with the exception of the core of the brush, with the result that not only a simple and light structure will be produced, but the frame when thus constructed will be rigid and durable and inexpensive to manufacture. 90 95

While the preferred form of construction has been herein shown and described, it is understood that various changes may be made in the details of construction and in the combination and arrangement of the several parts without departing from the spirit of 100 this invention.

What is claimed as new is:

1. A carpet sweeper embodying a casing 105 having a portion constructed of sheet material, an axle, wheels connected with the axle, and an anchor for the axle, said axle being fixedly connected with the anchor, a portion of the casing being offset to form a seat opening into the casing to loosely receive one end of the said anchor.

2. A carpet sweeper embodying a casing constructed of sheet material, a yielding axle, wheels connected with the axle, a portion of the casing being shaped to form a seat, said seat opening into the casing, and an anchor, said axle engaging at its central portion one end of the anchor and the other end of the anchor being seated in the said seat. 115 120

3. A carpet sweeper embodying a casing constructed of sheet material, a yielding axle, wheels connected with the axle, a portion of the casing being shaped to form a seat, said seat opening into the casing, an 125

anchor, said axle engaging at its central portion one end of the anchor, and the other end of the anchor being seated in said seat, and a handle bail pivotally connected with the casing, said portion of the casing extending beyond the outer face of said casing to form an abutment for the handle bail.

5 In testimony whereof I have signed my

name to this specification, in the presence of two subscribing witnesses, on this 7th day of 10 July, A. D. 1915.

FRANKLIN A. UMSTED.
